COINCIDENCE DETECTOR OF THE FOCUSED
ROTARY ELECTRON BEAM KINDRaymond R. Schramm, Bloomfield, N. J., assignor
to National Union Radio Corporation, Orange,
N. J., a corporation of Delaware

Application September 14, 1949, Serial No. 115,588

10 Claims. (Cl. 315—21)

1

This invention relates to electron tubes, and more particularly it relates to apparatus employing tubes of the focussed rotating electron beam kind such as disclosed in U. S. Patents #2,433,403 and #2,217,774.

A principal object of the invention is to provide an improved electron tube of the focussed rotating electron beam kind.

Another object is to provide a focussed rotary electron beam tube having at least two separate sets of electron beam control cages which are excited from two separate multi-phase sources to determine or control the relative phase relations of the waves from said sources.

Another object is to provide an improved phase-comparing or controlling apparatus employing a novel construction of focussed rotary beam tube.

Another object is to provide an improved coding arrangement employing a novel construction of focussed rotary beam tube.

Another object is to provide an improved multiplex signalling system employing a novel construction of focussed rotary beam tube.

A feature of the invention relates to an electron tube having a central electron-emitting cathode which is surrounded by a series of electrostatic beam-focussing and rotation controlled electrodes, and by a similar series of other electrostatic beam-controlling electrodes, both series being excited by respective plural phase alternating currents whereby the amount of space current passing to any one of a series of output anodes is a function of the relative phases of the said two excitations.

Another feature relates to a focussed electron rotary beam tube having separate series of surrounding electrodes which are energized by respective multi-phase voltages to enable the tube to be used as a multi-channel coincidence detector.

A further feature relates to the novel organization, arrangement and relative location and interconnection of parts which cooperate to provide an improved electron tube of the rotary focussed beam kind.

Other features and advantages not specifically enumerated, will be apparent after a consideration of the following detailed descriptions and the appended claims.

In the drawing,

Fig. 1 is an elevational view, partly schematic, of a tube according to the invention.

Fig. 2 is a cross-sectional view of Fig. 1, taken along the line 2—2 thereof.

2

Fig. 3 is a schematic circuit diagram showing one typical application of the tube of Figs. 1 and 2.

Figs. 4, 5 and 6 are respective wave diagrams explanatory of Fig. 3.

Referring to Figs. 1 and 2, the numeral 1 represents any suitable evacuated enclosing bulb or envelope within which is supported an electrode assembly or mount 2 according to the invention.

10 The tube 1 may be provided with any usual base 3 carrying the various contact prongs 4 which are connected to the respective electrodes of the mount 2. The mount or electrode assembly 2 comprises a central electron-emitting cathode 5 which is preferably of the indirectly heated type, comprising a cylindrical metal sleeve 6 having its external surface provided with a coating of electron-emissive material. Suitably located within the sleeve 6 is any well-known heater wire or element 7 for raising the said coating to its electron-emissive temperature. Concentrically surrounding the cathode 5 is a cylindrical metal cage consisting of a series of metal slats 8—13. Each of these metal slats is equally spaced from the adjacent slats to provide a series of windows 14—19. Likewise, each slat is provided throughout its central length with a grid or electron permeable window 20—25. For a detailed description of a typical construction for such a cage, reference may be had to the article published in the "Proceedings of the I. R. E.", volume 36, number 11, November, 1948, entitled "Electrostatically Focussed-Radial Beam Tube," and also as disclosed in the prior Patent #2,433,403. The construction of this cylindrical cage is such that in effect it provides a series of equally-spaced electron permeable windows. While the drawing shows twelve such windows formed from six metal slats, it will be understood that a greater or less number may be employed, as will be apparent from the ensuing description. In any event, each of the slats is provided with a separate lead-in as indicated by the numerals 26—31 in the schematic showing of Fig. 3.

15 The slat electrodes 8—13 are arranged to be connected to a suitable source of six-phase alternating current supply represented schematically in Fig. 3 by the block 32. Each of the six-phase windings of the source 32 is connected to a respective one of the slats 8—13 so that the excitation of each slat is 60° out of phase with the excitation of the adjacent slat. The cathode 5 is arranged to be connected to a suitable positive biasing potential so that in conjunction with the excitation voltages applied to the slat 8—13,

the electrons are formed into a single-ended beam which is substantially focussed at the surface of each of the slats, and it also rotates around the axis of the cathode and past each slat at a rate determined by the cyclic frequency of the six-phase source 32, as explained in detail in the prior article in the "Proceedings of the I. R. E." and in the prior Patent #2,433,403.

Concentrically surrounding the slats 8-13 is another series of similar slats 33-38, each slat having a central longitudinal grid or electron permeable window 39-44. The slats are spaced apart circumferentially to provide a series of windows 45-50 in radial alignment with the respective windows 14-19. Likewise the grids or windows 39-44 are in radial alignment with the corresponding windows or grids 29-25. Mounted in radial alignment with each of the windows 39-50 are respective control grids 51-52, each of which may comprise a pair of side rod supports, for example 63, 64, around which is wound the usual fine grid wire 65. Mounted in radial alignment with each grid is a respective anode 66-71. All the anodes may be connected through a common load resistor or impedance 73 and to a source of positive direct current plate supply voltage represented by battery 79, whose negative terminal may be grounded. Each anode is likewise connected through an individual coupling condenser 82-91, to a respective output channel 30 or utilization device 92-103.

The slats 33-38 of the second cage are connected through their respective lead-in conductors 104-109 to corresponding respective phases of a six-phase alternating current source 110 which may be similar to source 32.

The focussed electron beam 111 rotates continuously in the direction of the arrow at a uniform rate determined by the frequency of source 32, and as explained in said I. R. E. publication and in said patents. Consequently, the beam will successively and recurrently pass through the windows 8-19 of the first cage. If the voltage conditions supplied by source 110 at the corresponding windows 39-50 of the second cage are in the proper phase relation at the instant the beam passes through the corresponding window of the first cage, electrons will pass through the respective window of the second cage and thence through the respective control grid 52, etc. to the respective output anode 66, etc.

It is clear therefore, that electron or space current can flow from the cathode to the successive anodes only when the multi-phase excitation fields applied to the first and second cages are in proper relative phase. Thus, if source 32 is a source of known fixed phase and frequency, and source 110 is a source of adjustable phase and/or adjustable frequency, the phase or frequency of source 110 can be adjusted until a signal of predetermined uniform amplitude reaches each of the respective devices 92-103. Merely for explanatory purposes, the devices 92-103 may be pilot lamps, and if the beam 111 rotates at a sufficiently high speed, the simultaneous illumination of all the lamps to the same degree of illumination will show that the two sources 32 and 110 are in like phase and synchronism. It will be understood, of course, that this detection of in-phase or synchronism can be determined in any other suitable manner, for example the devices 92-103 may represent deflection plates surrounding a central electron beam of a cathode-ray tube. If the excitation of these plates is uniform, indicating synchro-

nism between the two sources 32 and 110, the beam of the cathode-ray tube will scan a uniform pattern. Any lack of phase or synchronism will then be indicated in this uniform pattern on the screen of the cathode-ray tube.

From the foregoing, it will be seen that when the two sources 32 and 110 are in like phase or synchronism, pulses of equal amplitude will reach the devices 92-103. It may be desirable to produce these pulses only when the beam is passing through the central portion of each of the aligned windows in the two cages. For this purpose the control grids 66-71 can be connected to ground through a suitable adjustable negative direct current biasing source 112. This enables the portion of each cycle over which coincidence is registered between the rotating electron beam 111 and the portion of the window in the second cage through which it is passing, to be narrowed in angular extent, and permits a much higher degree of synchronization of the phases of the sources 32 and 110 to be obtained. The accuracy thus obtainable in the synchronization of the phases is then a mere matter of physical construction determined by the size of the windows in the two cages and the characteristic of the control grids.

Merely by way of example, let it be assumed that the electron beam 111 is rotating at a speed $2\pi f_0$ caused by a six-phase voltage applied to the six slats 8-13, where f_0 is the frequency of the six-phase supply. If the six-phase supply applied to the slats 33-38 of the second cage is in phase synchronism with the first supply, then the wave form of the anode current would be as indicated in Fig. 4. Should the six-phase voltage from source 110 be out of phase with the voltage from source 32, a smaller total anode current or no anode current at all will flow.

It will be understood, of course, that the invention is not limited to the comparison of two sources of the same frequency. For example, if the source 110 has a frequency twice that of source 32, and if at the beginning of an observation the two sources are in phase, the anode current would be as indicated in Fig. 5. Similarly, if the frequency of the source 110 is half the frequency of source 32, and if the observations start at the instant the two sources are in phase, the anode current would be as indicated in Fig. 6. In other words, should the frequency of rotation of the two electrostatic fields applied respectively to the first and second cages be related by an integral number, the current to each anode will follow a definite sequence. For example, should the two sources be equal in frequency and phase (assuming six-phase sources), current will flow to anodes 66, 67, ..., 71 in sequential order. Should however, the frequency of the field applied to the second cage be non-integral with relation to the frequency applied to the first cage, for example in the ratio of 19 to 7, the current would flow to the respective anodes in the following sequence (assuming of course six-phase supply is used and twelve windows in each cage): 66, 73, 68, 75, 70, 77, 72, 67, 74, 69, 76, 71. Thus, by controlling the relative frequencies of the two sources, it is possible to determine the order in which each anode receives electron or space current. Consequently, by applying separate signal potentials to the input signal devices 113-124, it is possible to transmit coded intelligence. For example, each of the sources 113-124 may represent a corresponding multiplex input channel, and the devices 92-103 would represent corresponding mul-

triplex output terminals. The coding of the transmission to the various channels can then be controlled either by changing the relative phases of the two sources 32 and 110; by changing their relative frequencies; or by changing both their relative frequencies and their relative phases.

While in the foregoing, reference has been made to six-phase sources and to cages having twelve windows with twelve corresponding control grids and anodes, it will be understood that this is done merely for purposes of explanation and that a greater or less number of phases and corresponding windows, control grids and anodes, can be employed without departing from the spirit and scope of the invention. Thus while in the foregoing the tube has been disclosed as of the type wherein the beam is electrostatically focussed, it will be understood that the focussing and rotation of the beam can be effected electromagnetically as disclosed for example in U. S. Patent #2,217,774 and as described in the "Journal of Applied Physics," volume XV, No. 10, pages 704, 709, October 1944.

What is claimed is:

1. Electron discharge tube apparatus having means to develop a rotating electron beam and including a central electron-emitting cathode, a first cage electrode having a series of sections defining electron permeable windows concentrically surrounding said cathode, means to excite said sections by respective phases of a first multi-phase potential source; a second cage electrode surrounding the first cage electrode and having a series of sections defining electron permeable windows in radial alignment with the first mentioned windows but displaced radially therefrom, means to excite the sections of said second cage with the respective phases from a second multi-phase potential source, a plurality of anodes respectively aligned with said windows, and means to adjust the phase of one of said sources to produce recurring pulses of current at said anodes whose time spacing is controlled by the phase relation between said sources.

2. Electron discharge tube apparatus according to claim 1, in which said anodes are radially aligned with said windows.

3. Electron discharge tube apparatus according to claim 1, in which a series of control grids are located one between each anode and the radially aligned windows of said cage electrodes.

4. Electron discharge tube apparatus according to claim 1, in which one of said sources is of known fixed phase and the other of said sources is of adjustable phase.

5. Apparatus for detecting phase relations between two multi-phase signals comprising an electron discharge tube of the focussed rotary electron beam type and having a first cage electrode with a plurality of sections defining electron permeable windows through which the focussed beam is arranged to pass during its rotary motion; a second cage electrode surrounding the first cage electrode and having a series of sections defining electron permeable windows in alignment with the first-mentioned windows and radially displaced therefrom, a plurality of anodes each in alignment with said windows, and means to apply respectively to said cage electrodes the signals whose relative phases are to be determined, to produce recurring current pulses at said anodes whose time spacing is determined by the said relative phases.

6. Apparatus according to claim 5, in which

an elongated electron emitting cathode is concentrically mounted within said first cage.

7. Apparatus according to claim 5, in which said first cage consists of "n" sections defining $2n$ windows, and the source of multi-phase signals is connected to said sections to provide $2n$ excitation phases.

8. Apparatus according to claim 5, in which each of said cages comprises a series of sections which define $2n$ windows where "n" is the number of sections, and the multi-phase signal applied to one of said cages provides $2n$ phases.

9. Apparatus of the type described, comprising, means to develop two multi-phase signals whose phases are to be compared, a central electron-emitting cathode, a series of separate electrode members surrounding the cathode of define electron permeable windows between said members, each of said members having an individual electron permeable window, means connecting the phases of one of said signals respectively to said sections, another cage electrode surrounding the first cage electrode and having electrode members defining electron permeable windows between adjacent members and with each member also having an individual electron permeable window in the body thereof, the windows in both said cages being in radial alignment with each other but radially spaced from each other, means to apply the phases of the other multi-phase signal to the electrode members of said second cage, a plurality of output anodes one for each of the electron permeable windows in the second cage, and means for adjusting the phase of one of said multi-phase signals with respect to the phase of the other multi-phase signal to produce recurring current pulses at said anodes whose time spacing is controlled by the relative phase between said signals.

10. In combination, an electron discharge tube of the type having an electron-emitting cathode, a first multi-windowed cage surrounding the cathode for developing therewith a focussed electron beam, means to apply a first multi-phase potential to said first cage electrode, a second multi-windowed cage electrode surrounding the first electrode and with the windows thereof in radial alignment with those of the first electrode and radially spaced therefrom, means to apply a second multi-phase potential to said second electrode, a plurality of output anodes one for each of the sets of said radially-aligned windows, a control grid for each anode, a plurality of signalling channels each connected respectively to one of said control grids, and means to adjust the relative phase relations between first and second multi-phase potentials to produce recurring current pulses in said channels with the time spacing between pulses correlated with the phase difference between said two potentials.
